(57) **CLAIM**

An ornamental design for a bib, as shown and described.

DESCRIPTION

FIG. 1.1 is a front perspective view of our new design for a bib in a fully fastened position;

FIG. 1.2 is another perspective view thereof;

FIG. 1.3 is a back side perspective view thereof fastened in a first position;

FIG. 1.4 is a left side elevational view thereof;

FIG. 1.5 is a top plan view thereof;

FIG. 1.6 is another back side perspective view fastened in a second position;

FIG. 1.7 is another back side perspective view thereof;

FIG. 1.8 is a front side perspective view thereof in a fully unfastened position;

FIG. 1.9 is a top view thereof in a partially unfastened position;

FIG. 1.10 is a rear view thereof; and

FIG. 1.11 is a top view thereof in another partially unfastened position.
